UNITED STATES PATENT OFFICE.

JAMES M. FIX, OF BIRD'S LANDING, CALIFORNIA.

GANG-PLOW.

SPECIFICATION forming part of Letters Patent No. 285,885, dated October 2, 1883.

Application filed February 5, 1883. (Model.)

To all whom it may concern:

Be it known that I, JAMES M. FIX, of Bird's Landing, county of Solano, State of California, have invented an Improved Gang-Plow; 5 and I hereby declare the following to be a full, clear, and exact description thereof.

My invention relates to certain new and useful improvements in that class of gang-plows in which the axle is pivoted and is adapted to 10 be moved obliquely with the line of travel, whereby it is specially serviceable for side-hill work.

My invention consists in certain details of construction and combinations of devices, as 15 hereinafter fully described and claimed.

Referring to the accompanying drawings, Figure 1 is a perspective view of my plow. Fig. 2 is a cross-section showing racks G and guards d.

20 Let A. A represent the plow-beams, and B the tongue or draft-bar.

C is the axle, having on each end the loose cranks D, to the ends of which the wheels E are journaled.

25 In plows of this description there are always levers F secured to the cranks D, whereby said cranks may be turned to raise and lower the plows. These levers engage with racks G, and are held to place either by separate springs, or 30 the levers may be made as here shown, the lower part, e, being of spring material. Now, my first improvement relates to these racks.

In gang-plows, especially those intended for side-hills, it has been found desirable to so 35 connect the axle with the beams that by suitable means the axle may be turned obliquely to the line of travel or draft in order to get to or from the land with more precision, and to 40 avoid slipping. This is accomplished by pivoting the axle at a, and providing a guide, b, for it at the other side. A rod, c, joins the axle with the lower end of a lever, H, pivoted to the back of the beam, and engaging suitably through a pawl with a rack, I. By operating 45 this lever the axle may be drawn or forced in a position obliquely to the line of travel. This construction is now well known, and it suggests three points, which lead to my improvement, as I shall explain. At first, when 50 the axle was stationary, the racks G were secured to the beams A; but when the axle was rendered adjustable, as I have explained, it

became necessary to remove the racks from the beams, because the levers F, being attached to the axle or to the cranks, moved with said axle and no longer engaged the racks with precision, as these, being on the beam, were stationary. The racks, therefore, had to be in some manner connected with the axle to move with it. They were accordingly secured 55 upon top of high standards extending upward from the axle, and there they now remain; but the objection to this is that by the intervention of the bridge or support formed by these standards the racks are raised so high 60 that the strain of the levers, when engaged therewith, acts through said standard as through a lever, and brings entirely too much strain upon the axle. Every time the levers are thrown into engagement with the racks a 65 strain is placed upon the axle through the leverage of the standards supporting the racks. The axles used cannot well bear this strain, as they are made small in diameter, and it is a difficult matter to keep them from twisting. 70

75 My improvement consists in doing away with the strain by bolting the racks right down on the axle. To adapt the axle for this purpose, and to make it better able to resist what little strain there is, I make it wide. 80 Thus it will be seen that my racks G are bolted down solidly on the axle, and that the latter is made very wide. The racks, levers, and axle may be made of any suitable material. The strain of the levers F, when thrown into engagement with the racks, will not be transmitted to the axle to any extent, because there is no purchase.

85 Another improvement consists in the adaptation of the cranks D to receive the wheels at 90 either end. The wheels are usually placed out of line, but some may desire to have them brought nearer if not quite in line. I may take out the spindle or journal J from one end of the crank and insert it in the other end, 95 transferring the scraper usually placed on these plows to the first end.

100 My next improvement consists in a guard and protector for the spring of the levers F. When the lever once engages with the teeth of the rack, it is sometimes hard to disengage it, and the operator is required to use a sudden force. When this is done, the springs e, forming the lower end of the lever, and which hold

it in engagement, are liable to be bent or broken. To obviate this difficulty, I have a guard-strip, *d*, bolted to the lever and extending over the rack, and bent down behind it at a short distance therefrom just enough to allow the complete disengagement of the lever from the rack-teeth. When it is suddenly and forcibly thrown out it, frees itself, but no more, as the guard *d* comes in contact with the edge 10 of the rack, and prevents its further movement outwardly, thus protecting the spring *e*. The guard *d* is therefore not so much of a guide as a protector, and therein differs from the ordinary guides resembling it, which are attached 15 to sliding levers and embrace the racks closely. Such levers are held in engagement by a separate pawl mechanism, and their operation is simply to slide along the rack when their pawl is disengaged. They have no springs to be 20 strained, and therefore need only a guide and not a guard, such as I have shown to be necessary in case of a spring-lever.

When the plow is moving on the road or on rough land, it may happen that the levers *F* 25 will not remain in engagement with their racks. In order to lock them therein, when necessary, I have the following device:

Pivoted upon the inside of the levers *F* are short levers *P*. The lower ends of these are 30 bent inwardly and backwardly, forming a point which is in position to enter between the guard *d* and the inner edge of the rack, or to be withdrawn therefrom by the movement of the upper end of the levers *P*. These upper 35 ends are formed of a spring-strip, and are adapted to engage with a short cross-rack, *p*, upon the main levers, to hold their lower ends in or out of engagement with the guards *d*. When thrown in, they lock the guards *d*, so 40 that the levers *F* cannot spring out, and when drawn back they release them.

Having thus described my invention, what I claim as new, and desire to secure by Letters Patent, is—

1. In a gang-plow, the cranks *D*, having a bearing at each end adapted to receive the 45 wheels forward or back, substantially as herein described.

2. The racks *G*, in combination with the spring-levers *F*, having bifurcated spring ends 50 *e* *e*, and the guards *d* for limiting the movement of said levers in disengaging themselves from the rack, and the means for locking said levers in the racks, consisting of the spring-levers *P*, engaging with racks *p*, the lower ends 55 of said levers being adapted to enter between the guards *d* and racks *G*, or to withdraw therefrom, substantially as and for the purpose herein described.

3. In a gang-plow, the pivoted axle *C*, having the cranks *D* for the wheels, and a means for turning said axle obliquely with the line of travel, in combination with the levers *F* for operating cranks *D*, and their corresponding racks *G* bolted down directly upon the axle, 60 substantially as and for the purpose herein described.

4. In a gang-plow, the pivoted axle *C* and the racks *G*, bolted down directly thereon, said axle being made wide to form a secure and 70 rigid bearing for said racks, in combination with the cranks *D* and the levers *F*, operating them and engaging with said racks, substantially as and for the purpose herein described.

In witness whereof I hereunto set my hand. 75

JAMES M. FIX.
